UNITED STATES PATENT OFFICE.

DAVID ZORK, OF CHICAGO, ILLINOIS.

EXTENSION TABLE.

Application filed September 12, 1924. Serial No. 737,251.

This invention relates to a novel and improved extension table and has for its primary object the provision of such a table which may be used in extended position 5 without the necessity of moving the supporting legs or base.

A further object is to provide an extension table to which leaves may be added without marring the ornamental appearance thereof. 10 A still further object is to provide a table which will, in its normal position, give no indication of being an extension table, and which, when extended, will still preserve its good appearance.

15 Another object is to provide means for extending a table which will not require fastening means such as those commonly used.

Still another object is to provide an extension table which shall be rigid in construction and wherein the extended portion will not sag.

In the drawings in which I have illustrated one embodiment of my invention,

20 Fig. 1 is a plan view of my improved table without the extension leaves.

Fig. 2 is an elevation of my improved table, a portion thereof being shown in section, and showing the extension leaves in 25 position.

Fig. 3 is a section on the line 3—3 of Fig. 1.

Fig. 4 is a section on the line 4—4 of Fig. 1.

30 Fig. 5 is a section on the line 5—5 of Fig. 2, and

Fig. 6 is a perspective view of one of the extension leaves.

Referring now to the drawings, the 35 numeral 1 designates any suitable rigid base which, in this embodiment, I have shown as comprising a plurality of legs 2, and on this base I mount a frame comprising side members 3 and end members 4 which support the sides 5 and ends 6, respectively.

The sides 5 are rigidly connected to the side members 3 and are preferably recessed as at 7 to receive said side members. Similarly, the ends 6 are recessed as at 8 to receive the end members 4 but they are not rigidly secured thereto, for a purpose which will presently appear. Supported on the sides and ends are beaded members 9 which in turn carry the top 10. The beaded members are secured together by the tie members

11 and the side members 3 are secured together by the tie members 12.

Mounted on the side members 3 of the frame are a plurality of guide strips 13 forming guides for the slides 14 and 15, as 40 will be noted. These slides are snugly received in the space between the frame members 3 and the tie members 11, only as much play being allowed as is necessary to permit sliding movement therebetween. As will be 45 best seen from an inspection of Fig. 1, the slides 14 support one of the ends 6 and the slides 15 support the other of said ends, whereby said ends may be drawn out to the positions shown in dotted lines in Fig. 1. 50 Longitudinal movement of the slides is limited by means of the pins 16 which engage stops 17 secured to the guide members 13 or to any other fixed part of the table.

When the slides are in their extended 55 position they are held firmly therein not only by engagement with the members 3 and 11, as stated above, but also by snug engagement with the guide members 13 so that leaves placed on the slides will form a perfect continuation of the top 10. When the slides are in their innermost position the ends are supported by the end members 4 through engagement of said members in the recesses 8, and are preferably beveled, as 60 shown at 18, to fit the sides so that a very close inspection, indeed, is necessary to distinguish the table from one which is not adapted to be extended.

As I have shown in this embodiment, the 65 top and beaded members overlie the sides to a substantial extent, thus further concealing the joints between the ends and sides.

When the slides are in the extended position shown in dotted lines in Fig. 1, they are 70 adapted to receive leaves. One of these leaves is shown in Figs. 5 and 6, and referring thereto it will be seen that it comprises a top 19 supported by beaded members 20 which correspond to and match with the 75 beaded members 9 and which are supported by sides 21 corresponding to and matching with the sides 5. On the underside of each top are secured spacing members 22 to fill the space between the underside of the top 80 and the upper side of the slides. Carried by said spacing members 22 are guiding members 23 adapted to contact with the sides 85 of the slides and maintain the leaves against lateral movement with respect thereto. By 90

110

providing these guiding members and placing them so that they fit snugly against the slides I find it unnecessary to provide other fastening means, such as the dowels which are common in extension tables now in use and the disadvantages of which are well-known. The sides 21 are beveled at their end edges to register with the beveled edges 18 of the ends 6 and with the corresponding- 10 ly beveled edges of the sides 5 or other sides 21, as the case may be. The beaded members 20 of the leaves will match with the beaded members 9 and the beveled edge 19' of the top 19 will register with the edge of 15 the top 10, thereby providing a structure which gives to the eye the appearance of having been built in that form.

From the above it will be seen that I have provided a novel and improved table which 20 may be extended without depriving it of its ornamental appearance and without lessening its rigidity. The base is stationary at all times and does not have to be disturbed in order to extend the table, as is customary 25 with the type of extension table now in general use and which has been found to quickly lose its rigidity after in use a short time. By providing the guiding members 23 I make it possible, as I have noted above, to 30 dispense with the common fastening and alignment means normally placed between the edges of the leaves and which would obviously mar the edge of a table of the type which I have illustrated. I have found 35 my table, as described above, to be extreme-

ly satisfactory in use and to satisfy all requirements of rigidity and appearance which may be made by the most critical purchaser of high-class furniture.

I am aware that changes in the form, construction and arrangement of parts may be made without departing from the spirit and without sacrificing the advantages of the invention and I reserve the right to make all such changes as fairly fall within the scope 45 of the following claim.

I claim:—

An extension table comprising a plurality of legs, longitudinal side members rigidly mounted thereon, transverse tie members 50 connecting said side members, sides fixedly secured to said side members, beaded members fixed to said sides on the top thereof, top tie members connecting said beaded members, slides mounted on said side members between the top and transverse tie members and being wholly supported thereby, guides for said slides, means for limiting the movement of said slides, ends rigidly connected to said slides and movable therewith 60 and removable leaves mounted on the slides when extended, said leaves having an apron depending from each side thereof corresponding to said sides and spacing members secured to the under surface at the sides 65 thereof to contact with said extended slides to position said leaves in the same plane as the table top, and guides secured to said under surface for contacting with said slides.

DAVID ZORK.
